Primary Examiner—Freda Nunn*Attorney, Agent, or Firm*—Seed & Berry LLP[57] **CLAIM**

The ornamental design for a door for a data-storage-media library, as shown and described.

DESCRIPTION

FIG. 1 is a front perspective view of a door for a data-storage media library showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines are shown in the views for illustrative purposes only and form no part of the claimed design.
